UNITED STATES PATENT OFFICE

2,652,692

BREAKWATER CONSTRUCTION

David Homer Hayden, Sarasota, Fla., assignor,
by mesne assignments, to Beach & Shore, Inc.,
New York, N. Y., a corporation of New York

Application May 3, 1947, Serial No. 745,850

1 Claim. (Cl. 61—4)

1

The purpose of this invention is to provide a construction by which it is possible to easily and quickly build a breakwater or bar in shallow water, for instance on a beach, or the bank of a river or tidewater area without the use of coffer dams and so as to retain backfill from a dredge or other source. Also to provide crib piers in places where freezing tidewater or wave action might lift driven piles.

I accordingly provide unit frames small enough to be handled by ordinary laborers without special equipment and designed so that they can be placed in any suitable position, superposed and connected in various ways.

The accompanying drawings illustrate a single unit and various ways in which they can be installed and united.

Fig. 1 is a perspective view of a single unit frame on a small scale embodying my invention.

Fig. 2 is a fragmentary sectional view taken on the plane of the line 2—2 of Fig. 1 but on a larger scale.

Fig. 3 is a perspective view of a part of the frame on a scale larger than Fig. 1 but smaller than that of Fig. 2.

Fig. 4 is a view illustrating my invention installed on a beach line and showing the bottom and high water level line.

Figs. 5, 6, 7, 8 and 9 are diagrammatic views showing different arrangements embodying my invention.

The interchangeable units may be of various sizes and shapes such as the square frame 10 of Fig. 1 of a convenient size such as 4 ft. x 4 ft., each side being of a cross section of 6 in. x 2½ in. Such a size can be easily handled by two men.

Such a frame is preferably cast in a single piece of concrete and preferably with steel reinforcement such as rods 11, 11. The sides of each unit are provided with holes 12, 12 which have two functions i. e., to serve as weep holes for the circulation of water and sand and also to accommodate tie rods, bolts, chains or cables for uniting adjacent units. The upper and lower edges of each unit are provided with flanges 13 and 14, respectively. The lower flanges 14 of the bottom frame serve to cut into the sand or other beach soil and the upper flanges 13 of one unit overlap the lower flanges of the next upper frame.

Fig. 4 shows a stack of units installed on the bottom 15. High water level is indicated by the line 16. The dotted line 17 indicates the probable line of a wash-in backfill. When units are arranged in a stack as shown in Fig. 4 the various

2

layers may be connected by vertical reinforcing bars 18, 18 outside or inside and united in any suitable manner.

The unit frames may be installed in various ways depending upon the local conditions. For instance units 10—10 are spaced apart in Fig. 5 and connected by wall sections 20—20. These may be united by bars or cables 21 passed through holes such as 12, 12 of Figs. 1 and 2 and around the corners of the frames.

In Fig. 6 the spaced units 10—10 in one row are connected by interposed units 10'—10' in a parallel row united by cross bars 22. The dotted outlines 23 indicate the possible addition of other units.

In Fig. 7 the frames are set up in a diagonal arrangement where adjacent units are connected by bolts 24, 24 and the dotted lines 25 indicate possible additional units.

Fig. 8 shows a zig-zag arrangement of frames 10 which can be united in any suitable manner and reinforced along the dotted lines 26 if desired.

Fig. 9 shows still another arrangement of two rows of units 16 and 27 connected by interposed units 29 and united for instance by ties 28.

Such units can be placed, one at a time, along the length of a wall and built up layer by layer. This can be erected in spite of continued wave action during which particles of sand or mud in suspension will be retained by the placed units. The relatively thin lower edges of the bottom unit permits the frame to sink and lock in the sand or mud and prevent waves from cutting under.

The interlocking of units insures against failure due to sinking at soft spots or where there may be a current of water. The connection of the units permits a considerable flexibility of the installation.

This type of construction causes the water to churn at the line of construction and reduces the cutting action of the waves and retards the backwash thus causing suspended particles to deposit at the line of construction.

This type of wall is especially applicable for constructions such as causeways, reclaiming land where wide flats exist and the like.

The unit frames can be arranged as pierhead or bridge abutment and tied vertically and horizontally in any suitable manner.

The angular shape of the frame units causes violent churning of the waves from the outside of the frames. Any number of weep holes may be provided and in positions which facilitate the

connection by vertical or horizontal connectors. The suspended sand or mud which is driven in through the weep holes or through the joints between the superposed frames therefore tends to stay inside the frames when the water flows out. In some cases it may be desirable to provide projections at intervals along the edges of each frame unit so that the main portions of the superposed units will be sure to be spaced apart slightly.

I claim:

A breakwater comprising a row of stacks of rectangular, one-piece, concrete frames spaced apart from each other in a line, a rectangular frame between each of the first mentioned spaced frames and in a line parallel to but out of line

with the spaced frames and means for connecting adjacent frames in the respective stacks.

DAVID HOMER HAYDEN.
